UNITED STATES PATENT OFFICE.

BERNARD BERNHEIM, OF LOUISVILLE, KENTUCKY.

DESIGN FOR A FLASK OR BOTTLE.

SPECIFICATION forming part of Design No. 32,425, dated April 3, 1900.

Application filed December 30, 1899. Serial No. 742,174. Term of patent 14 years.

To all whom it may concern:

Be it known that I, BERNARD BERNHEIM, a citizen of the United States, residing in the city of Louisville, county of Jefferson, in the State of Kentucky, have invented and produced a new and original Design for Flasks or Bottles, of which the following is a specification, reference being had to the accompanying drawings, forming part thereof.

Figure 1 is a view of the concaved side of my flask. Fig. 2 is a side elevation of the narrower side of the flask, and Fig. 3 is a top plan.

As shown in the drawings, the essential or material feature of my design consists in the concavo-convex configuration—to wit, the side A being convexed laterally, as shown, and the opposite side A' being concaved laterally, the convexed and concaved sides being on perpendicular lines to the longitudinal axis of the flask and in the same perpendicular plane throughout, thus producing a

flask of equal thickness throughout, as seen in Fig. 2, the concave side A', by reason of the shape of the flask, being slightly shorter laterally or narrower than the convex side A, as can be plainly seen in Fig. 3.

The edges or narrower sides B' of the flask are, as shown, made convexed, as can plainly be seen in Fig. 3, and the top portions *a* of these narrower sides being rounded off toward the central or neck B of the flask. I have shown the flask as provided with a cap C, screwed onto the neck of the flask.

Having described my invention, what I claim as new, and desire to secure by Letters Patent, is—

The design for a flask or bottle as herein shown and described.

BERNARD BERNHEIM.
